(57) **CLAIM**

The ornamental design for a keg coupler, as shown and described.

DESCRIPTION

FIG. 1 is a front perspective view of a keg coupler showing our new design;

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof; and,

FIG. 8 is a rear perspective view thereof.

The broken lines in the drawings represent unclaimed portions of the keg coupler and form no part of the claimed design.
